(57) **CLAIM**

The ornamental design for a single molded device for shredding and storing herbs, as shown and described.

DESCRIPTION

FIG. 1 is a top perspective view embodying the inventive single molded design showing the lid open and not yet detached from the body of the storage device;

FIG. 2 is a bottom perspective view of the device as seen in FIG. 1;

FIG. 3 is a left side view of the device as seen in FIG. 1;

FIG. 4 is a front view of the device as seen in FIG. 1;

FIG. 5 is a right side view of the device as seen in FIG. 1;

FIG. 6 is a rear view of the device as seen in FIG. 1;

FIG. 7 is a top view of the device as seen in FIG. 1;

FIG. 8 is a bottom view of the device as seen in FIG. 1;

FIG. 9 is a top perspective view embodying the inventive design showing the lid held into place via the latch, and after the single molded device was separated into two pieces by breaking the hinge originally attaching the lid to the body;

FIG. 10 is a bottom perspective view of the device as seen in FIG. 9;

FIG. 11 is a left side view of the device as seen in FIG. 9;

FIG. 12 is a front view of the device as seen in FIG. 9;

FIG. 13 is a right side view of the device as seen in FIG. 9;

FIG. 14 is a rear view of the device as seen in FIG. 9;

FIG. 15 is a top view of the device as seen in FIG. 9;

FIG. 16 is a bottom view of the device as seen in FIG. 9; and,

FIG. 17 is an exploded top perspective view embodying the inventive design showing the device in two pieces, i.e., after the hinge originally attaching the lid to the body has been broken.

The broken line showing is for the purpose of illustrating portions of the article or environmental structure and forms no part of the claimed design.
